(57) **CLAIM**

The ornamental design for a capacity gauge, as shown and described.

DESCRIPTION

FIG. 1 is a isometric or perspective view of our new capacity gauge;

FIG. 2 is a bottom elevational view thereof;

FIG. 3 is a top elevational view thereof;

FIG. 4 is a left side elevational view thereof;

FIG. 5 is a right side elevational view thereof; and,

FIG. 6 is a front top elevational view thereof.

The bottom of the “capacity gauge” is not seen nor is it intended to be seen as part of this design.
